INDEX TO BE USED WITH TELEPHONE DIRECTORIES AND OTHER BOOKS

Filed Oct. 12, 1931

INVENTOR

Francis John Osuch

BY

Barthel & Barthel

ATTORNEY

UNITED STATES PATENT OFFICE

FRANCIS JOHN OSUCH, OF DETROIT, MICHIGAN

INDEX TO BE USED WITH TELEPHONE DIRECTORIES AND OTHER BOOKS

Application filed October 12, 1931. Serial No. 568,442.

This invention relates to indexing and covering devices, particularly designed for use with bound books such as directories and the like.

5 The principal object of the invention is to provide a novel indexing and covering device which may be applied to and removed from a bound book, without injuring or altering the binding or the leaves of the latter.

10 Still further objects of the invention will become readily apparent upon reference to the following detailed description and to the appended drawing disclosing a preferred embodiment of the same.

In the drawing,

Figure 1 is a partial perspective view of an embodiment shown in use with a bound book;

20 Fig. 2 is a partial sectional view of the same;

Fig. 3 shows the device in use with the bound book closed, and with a cover part of the device open;

25 Fig. 4 shows the cover part of the device in open position.

Referring to the drawing, it will be seen that the device includes a plurality of index leaves 1 slightly larger than the leaves of the bound book, the latter having a cover referenced 2. On those edges of the index leaves adjacent the open edge of the book are a plurality of alphabetical indices 3 which are adapted to project beyond the edges of the book leaves.

30 For mounting the index leaves there are provided a pair of transverse members 4, preferably in the form of angles, which are disposed outside of the leaves and to which the leaves are hingedly and permanently connected by bent wires 5, these having ends secured to the upper and lower edges of the index leaves and also having portions disposed in spaced holes of the angle members 4, to form swivels or hinges for the index leaves. The angle members are detachably secured by means of headed rivets 6 passing through key hole slots in the angles, to the back section of a cover 7, the back section being referenced 8.

It will be observed that the device comprises, in general, two groups of parts, one of which is the cover per se and the other of which includes the angles 4, the wires 5 and the index leaves 1. The last mentioned group, 55 may be secured to and removed from the first mentioned group as a unit, through the medium of the keyhole slots and headed rivets, and may be applied to a bound book, without injuring or permanently disturbing the leaves, 60 or original cover of the latter.

It will be observed that in order to remove the index from a bound book it is first necessary to slide the cover 8 and the indexing unit, relatively, so as to present the larger 65 portions of the keyhole slots to the rivet heads, after which the cover and the indexing unit may be separated. When so separated they may be removed from the bound book in a manner which will be obvious. To reapply the index to a bound book, it is first necessary to thread the leaves to be indexed between the indexing leaves, after which the index per se, and with it, the bound book, 70 may be applied to the cover, or vice versa. 75

It will be observed that the cover part may be made of any suitable material to give permanence thereto and may be provided with advertising matter in a manner that is well known. Further the indexing leaves may be 80 ruled on one side as indicated to provide spaces for favored numbers, and may also be provided with advertising matter if desired.

It will also be observed that while the members 4 are shown as permanently secured to 85 the leaves and removably secured to the cover it will be clear that but one of the members may be so constructed, the other one if desired may be permanently or detachably secured to the cover or permanently or detachably secured to the leaves.

Now having described the invention and a preferred embodiment of the same, it will be clearly understood that the scope of the invention is to be limited, not to the specific 95 details herein shown, but only by the claims which follow.

I claim:

1. An index for bound books comprising a back section adapted to fit against and cov- 100

er the bound edge of the book, members at the opposite ends of the back section and detachably secured thereto, and a plurality of separate index leaves hingedly connected to 5 said members, the latter and the leaves being applicable to and removable from the bound book as a unit with the index leaves interspersed among indexed leaves of the book.

2. In an index for bound books, a back section 10 adapted to fit against and cover the bound edge of the book, and an indexing unit, removable from and applicable to the back section, as a unit, the unit having members detachably fastened to the back section at opposite ends thereof, outside of said book, and index leaves hingedly and substantially permanently secured to said members.

3. In an index for bound books, a back section 20 adapted to fit against and cover the bound edge of the book, and an indexing unit, removable from and applicable to the back section, as a unit, the unit having members detachably fastened to the back section at opposite ends thereof, outside of said book, 25 and index leaves hingedly and substantially permanently secured to said members by elongated means running from the upper edges of the leaves upwardly to the upper member, and from the lower edges of the 30 leaves downwardly to the lower member.

4. In an index for bound books, a back section 35 adapted to fit against and cover the bound edge of the book, and an indexing unit, removable from and applicable to the back section, as a unit, the unit having members detachably fastened to the back section at opposite ends thereof, outside of said book, 40 and index leaves hingedly and substantially permanently secured to said members by elongated wires running from the upper edges of the leaves upwardly to the upper member, and from the lower edges of the 45 leaves downwardly to the lower member.

5. In an index for bound books, a back section 45 adapted to fit against and cover the bound edge of the book, members above and below the upper and lower edges of the book leaves and secured to and extending transversely across the back section, index leaves 50 between the members, and means hingedly connecting and extending from the upper and lower edges of the index leaves to the members.

6. In an index for bound books, a back section 55 adapted to fit against and cover the bound edge of the book, members above and below the upper and lower edges of the book leaves and detachably secured to and extending transversely across the back section, index 60 leaves between the members, and means hingedly connecting and extending from the upper and lower edges of the index leaves to the members.

7. In an index for bound books, a back section 65 adapted to fit against and cover the

bound edge of the book, members above and below the upper and lower edges of the book leaves and detachably secured to and extending transversely across the back section, index leaves between the members, and means 70 permanently and hingedly connecting and extending from the upper and lower edges of the index leaves to the members.

In testimony whereof, I sign this specification this 2nd day of October, 1931.

FRANCIS JOHN OSUCH.
